UNITED STATES PATENT OFFICE.

FRANK F. SINKS, OF CHICAGO, ILLINOIS, ASSIGNOR TO CONDRON & SINKS, OF CHICAGO, ILLINOIS, A CORPORATION OF ILLINOIS.

MONOLITHIC BUILDING CONSTRUCTION.

1,005,756.

Specification of Letters Patent. Patented Oct. 10, 1911.

Application filed December 17, 1909. Serial No. 533,539.

To all whom it may concern:

Be it known that I, FRANK F. SINKS, a citizen of the United States, residing at Chicago, in the county of Cook and State 5 of Illinois, have invented certain new and useful Improvements in Monolithic Building Construction, of which the following is a specification.

It has heretofore been proposed to produce a monolithic building construction comprising reinforced concrete walls, supporting columns, and floors, and many different arrangements of the reinforcing metallic members have been provided, many 10 of them with well recognized fundamental expectation of introducing such reinforcing metallic members into those regions of the concrete which will, because of the load of the structure, either the weight of the 15 structure or the applied load, be subjected to tension stresses but, so far as I am aware, with perhaps one or two exceptions, the floor portions of such monolithic structures have comprised supporting beams having a 20 depth materially exceeding their thickness, and these beams have, of course, formed downwardly projecting ridges below the ceiling surface, or lower surface of the floor, in such way as to cast shadows upon the 25 ceiling and thus materially reduce the intensity of light in the room. There have been few exceptions to this general practice where a floor slab of uniform thickness, without beams of any kind, has been produced but, so far as I am aware, the manner 30 of placing proposed reinforcements in the floors of such constructions, as well as the manner of placing reinforcements in the floors and beams of the other structures to 35 which I have referred, has been such as to make a careful analysis of the stresses due to the dead weight and to the applied loads practically impossible and a computation of the stresses difficult and inaccurate.

40 The object of my present invention therefore is to produce a monolithic building structure in which there shall be no supporting beams having a vertical depth exceeding the horizontal width, and in which 45 the floor reinforcement and the supporting columns shall be so relatively arranged and proportioned that the stresses due to weight

and applied load may be accurately analyzed and computed.

The accompanying drawings illustrate a 55 building constructed in accordance with my invention.

Figure 1 is an under plan view of a complete floor square and adjacent floor squares with four supporting columns; Fig. 2 is a 60 vertical section, the upper portion being on line *b*, *b* of Fig. 1 and the lower portion being on line *a*, *a* of Fig. 1; Fig. 3 is a diagram showing a progressive arrangement of the various reinforcements; Fig. 4 is a sectional view representing diagrammatically some of the reinforcements; Fig. 5 is a perspective view of one panel of the paneled ceiling construction, including four columns; Fig. 6 is a diagrammatic view showing how one of the inclosing slabs may be laterally displaced relative to others of the inclosing slabs of the same series, and Fig. 7 a vertical section showing a paneling of the floor surface instead of the ceiling surface.

By the term "column" as hereinafter used, I intend to indicate a load-resisting or carrying strut which may be either in the form of an ordinary column or otherwise 80 arranged, depending upon the position in which the floor is placed. By the term "slab" I intend to define a portion of the floor which, for the purposes of stress analysis, shall have a lateral or transverse extent very materially exceeding its depth, *i. e.*, its dimension in the direction of applied load. By "inclosing slab" I intend to designate my slab substitute for an ordinary beam, said slab serving, for the purposes of analysis, as a supporting boundary for an adjacent "inclosed" slab which will be entirely surrounded by inclosing slabs. As a general rule all of the inclosing slabs 85 will extend directly from column to column and be formed integral therewith, the column immediately adjacent the slab being provided with a flaring cap which, of course, is integral with the inclosing slab. As an occasional exception, where a panel 90 or opening of somewhat different character from the general panels is desired, one of the inclosing slabs may be laterally shifted so as not to extend from column to column,

but, instead, to extend from one inclosing slab to a companion inclosing slab at a point between the column-supported portions of said slabs.

- 5 My structure therefore comprises a plurality of load-sustaining columns 1, preferably arranged in two crossing series in the common manner. Each of these columns is provided, at its load-receiving end, with a 10 flaring cap 2 which, if desired, may be surmounted by a plate 3. Extending across the tops of the columns are groups of reinforcing members 7. The members 7 of each group are laterally spaced in accordance 15 with the load stresses, and each group has a lateral extent closely approximating the greatest dimension of the flared cap 2 3 of the column, and this group will be embedded in an inclosing floor slab 5 which 20 will have a lateral dimension or width very materially exceeding the thickness of the slab. The reinforcing members 7 for each slab 5 must extend through the regions of tension of that slab which, at the middle of 25 the slab between the columns are near the lower face of the slab. There are also regions of tension in each of these inclosing slabs and near the upper face thereof adjacent the column ends of the slabs, and there- 30 fore some of the reinforcing members 7 may be deflected upwardly through a neutral region and then carried over the columns adjacent the upper surface of the inclosing slab, as clearly indicated in Fig. 2. Some 35 of the members 7 may also be carried directly across the columns adjacent to what would be the extended floor face of the inclosing slab. It will thus be seen that the longitudinally-arranged reinforcement for 40 the slabs 5 should lie in two different horizontal planes. The bars lying in the upper plane may be separate from those in the lower, or the bars occupying one plane may be integral with those of the other, the 45 transition from one plane to the other being obtained by means of a bend in the bars, as indicated at 5^a in Fig. 4. For the sake of clearness the different parts of the bars are shown in Fig. 4 as lying in different 50 planes. In a construction wherein the bars are bent, they may, if desired, be arranged so that the portion lying in the upper plane extends some distance beyond the column, while the portion lying in the lower plane 55 extends to the middle of the adjacent column. By this arrangement the same amount of metal is obtained in the upper plane as in that portion of the lower plane which lies between the columns. 60 Thus far the reinforcement of the inclosing slabs will be somewhat similar to reinforcement which has been heretofore used except that the lateral extent of each group of reinforcement will materially exceed the 65 vertical depth of the slab, but the flaring

cap of the column, being integral with the inclosing slab, gives to the slab, at the points where the compressive stresses are the greatest, an additional depth which, however, does not interfere with the uniform lighting 70 of the ceiling, as is the case where a beam having a depth materially greater than its thickness is used. Between the inclosing slabs 5 the floor may be considered as an inclosed slab 6 which will, of course, have 75 tension regions near its lower face in its middle, and these tension regions will be reinforced by metal fabric or by two series of crossing reinforcing members 9 which will be properly spaced laterally, as clearly indicated in Fig. 3, in order to meet the load conditions, and the ends of these reinforcing members 9 will extend to a greater or lesser extent over the group of reinforcing members 7, thus entering, to a greater or lesser extent, the edges of the inclosing slabs so that the inclosed slabs may be considered thus far as being hung upon the inner edges of the inclosing slabs. If this were the only reinforcement provided, however, the weight of the inclosed slab together with the applied load, would tend to overturn the inclosing slabs because of their great width as compared to their depth. This is a condition which does not 90 exist in that type of monolithic floor construction wherein supporting beams are provided having a depth materially greater than the width. In order to overcome this difficulty I therefore provide the reinforcing 95 members 8 which are placed transversely of the inclosing slabs near their upper faces, as clearly shown in the upper part of Fig. 2, and these reinforcing members 8 are arranged throughout that portion of the 100 length of each inclosing slab which is between the columns, said reinforcing members being spaced from each other but lying more closely together at the middle of the beam, as is clearly indicated in Fig. 3. 105 These reinforcing members 8 extend beyond the lateral extent of the reinforcing members 7 to a greater or less extent as clearly indicated. The reinforcing members 8 serve a double purpose; (1) in that they carry 110 the tension due to negative moments resulting from the loads on the inclosed slabs, thereby restraining the sides of these slabs and hence reducing the positive moment in the inclosed slab, and (2) this reinforcement 115 reinforces the inclosing slabs against lateral bending and therefore the loads from the inclosed slabs are carried by the full width of the inclosing slabs instead of being carried only by the adjacent edges. 120 It will be noted that the reinforcement is so arranged that the stresses due to the dead load and all applied loads can be accurately analyzed and computed. The reinforcing material being arranged in simple recti- 125 130

linear lines extending in only two directions in the structure (thereby obviating the necessity for more than two layers of bars in one face of the slabs), a considerable saving is effected in labor in placing both the reinforcement and the concrete during construction. All of the slab reinforcement is independent of the column reinforcement, thereby giving great latitude to the manner of reinforcing the columns. Furthermore, the longitudinal reinforcement of the intersecting slabs 5 is independent of the reinforcement of the inclosed slabs 6. The inclosed slabs 6 being carried by the slabs 5, it is practicable to make openings anywhere in an inclosed slab, or to omit it altogether, without weakening the construction, thus readily providing for elevator and stair wells. Furthermore, any one of the intersecting slabs 5 may be made to intersect other slabs 5 elsewhere than at the column supports, as shown in Fig. 6, the stresses in these slabs still remaining determinate. It will be seen that the shifted slab 5' is carried by two opposite slabs 5 at points removed from the column supports 1^a, the position of the slab 5' providing for an elevator or stair opening extending into the space between the columns 1^a.

30 As indicated in Figs. 5 and 7, the ceiling or the floor may, if desired, be paneled by making the inclosed slabs 6 of less thickness than the inclosing slabs 5; thereby securing a great saving in concrete and hence 35 in dead weight. The manner of reinforcing the slabs 5 and 6 is the same, however, whether the ceiling or the floor be paneled or not.

I claim as my invention:

40 1. A monolithic structure comprising a concrete floor and a plurality of columns in substantially straight rows, groups of reinforcing members extending from column to column longitudinally through the floor
45 adjacent the lower face between the columns and adjacent the upper face across the columns, and each of said groups having a transverse extent exceeding the floor thickness, thereby forming a plurality of similarly extending inclosing floor slabs, other groups of reinforcing members extending through the floor transversely of the first groups adjacent the lower face between said first groups and adjacent the upper face
50 across said first groups, each of said last groups having a transverse extent exceeding the floor thickness so as to form a second series of inclosing floor slabs extending transversely between the first series of inclosing floor slabs thereby inclosing a multiplicity of inclosed floor slabs, a multiplicity of transversely arranged reinforcing members lying near the upper face of each inclosing slab between its ends, and two series
55 of crossing reinforcing members each ex-

tending through an inclosed slab and lying adjacent the lower face thereof.

2. A monolithic structure comprising a concrete floor and a plurality of columns in substantially straight rows, each having a flaring cap adjacent the floor, groups of reinforcing members extending from column to column longitudinally through the floor adjacent the lower face between the columns and adjacent the upper face across the columns, and each of said groups having a transverse extent exceeding the floor thickness, thereby forming a plurality of similarly extending inclosing floor slabs, other groups of reinforcing members extending through the floor transversely of the first groups adjacent the lower face between said first groups and adjacent the upper face across said first groups, each of said last groups having a transverse extent exceeding the floor thickness so as to form a second series of inclosing floor slabs extending transversely between the first series of inclosing floor slabs thereby inclosing a multiplicity of inclosed floor slabs, a multiplicity of transversely arranged reinforcing members lying near the upper face of each inclosing slab between its ends, and two series of crossing reinforcing members each extending through an inclosed slab and lying adjacent the lower face thereof. 95

3. A monolithic structure comprising a concrete floor and a plurality of columns in substantially straight rows, groups of reinforcing members extending from column to column longitudinally through the floor adjacent the lower face between the columns and adjacent the upper face across the columns, and each of said groups having a transverse extent exceeding the floor thickness, thereby forming a plurality of similarly extending inclosing floor slabs, other groups of reinforcing members extending through the floor transversely of the first groups adjacent the lower face between said first groups and adjacent the upper face across said first groups, each of said last groups having a transverse extent exceeding the floor thickness so as to form a second series of inclosing floor slabs extending transversely between the first series of inclosing floor slabs thereby inclosing a multiplicity of inclosed floor slabs, a multiplicity of transversely arranged reinforcing members lying near the upper face of each inclosing slab between its ends and extending into adjacent regions of the inclosed floor slab, and two series of crossing reinforcing members each extending through an inclosed slab and lying adjacent the lower face thereof.

4. A monolithic structure comprising a concrete floor and a plurality of columns in substantially straight rows, each having a flaring cap adjacent the floor, groups of re- 130

inforcing members extending from column to column longitudinally through the floor adjacent the lower face between the columns and adjacent the upper face across the columns, and each of said groups having a transverse extent exceeding the floor thickness, thereby forming a plurality of similarly extending inclosing floor slabs, other groups of reinforcing members extending 10 through the floor transversely of the first groups adjacent the lower face between said first groups and adjacent the upper face across said first groups, each of said last groups having a transverse extent exceeding 15 the floor thickness so as to form a second series of inclosing floor slabs extending transversely between the first series of inclosing floor slabs thereby inclosing a multiplicity of inclosed floor slabs, a multiplicity 20 of transversely arranged reinforcing members lying near the upper face of each inclosing slab between its ends and extending into adjacent regions of the inclosed floor slab, and two series of crossing reinforcing members 25 each extending through an inclosed slab and lying adjacent the lower face thereof.

5. A monolithic structure comprising a concrete floor and a plurality of columns in substantially straight rows, groups of reinforcing members extending from column to column longitudinally through the floor adjacent the lower face between the columns and adjacent the upper face across the columns, and each of said groups having a transverse extent exceeding the floor thickness, thereby forming a plurality of similarly extending inclosing floor slabs, other groups of reinforcing members extending 30 through the floor transversely of the first groups adjacent the lower face between said first groups and adjacent the upper face across said first groups, each of said last groups having a transverse extent exceeding 35 the floor thickness so as to form a second series of inclosing floor slabs thereby inclosing a multiplicity of inclosed floor slabs, transversely arranged reinforcement lying near the upper face of each inclosing slab between its ends, and reinforcement extending through an inclosed slab and lying adjacent the lower face thereof and extending into the adjacent inclosing slabs.

55 6. A monolithic structure comprising a concrete floor and a plurality of columns in substantially straight rows, each having a flaring cap adjacent the floor, groups of reinforcing members extending from column to column longitudinally through the floor adjacent the lower face between the columns and adjacent the upper face across the columns, each of said groups having a transverse extent exceeding the floor thickness, thereby forming a plurality of similarly 60 extending inclosing floor slabs, other groups of reinforcing members extending through the floor transversely of the first groups adjacent the lower face between said first groups and adjacent the upper face across said first groups, each of said last groups having a transverse extent exceeding the floor thickness, thereby forming a plurality of similarly 65 extending inclosing floor slabs, other groups of reinforcing members extending through the floor transversely of the first groups adjacent the lower face between said first groups and adjacent the upper face across said first groups, each of said last

tending inclosing floor slabs, other groups of reinforcing members extending through the floor transversely of the first groups adjacent the lower face between said first groups and adjacent the upper face across 70 said first groups, each of said last groups having a transverse extent exceeding the floor thickness so as to form a second series of inclosing floor slabs extending transversely between the first series of inclosing floor slabs, thereby inclosing a multiplicity of inclosed floor slabs, a multiplicity of transversely arranged reinforcing members lying near the upper face of each inclosing slab between its ends, and two series of crossing reinforcing members each extending through an inclosed slab and lying adjacent the lower face thereof and extending into the adjacent inclosing slab.

7. A monolithic structure comprising a concrete floor and a plurality of columns in substantially straight rows, each having a flaring cap adjacent the floor, groups of reinforcing members extending from column to column longitudinally through the floor adjacent the lower face between the columns and adjacent the upper face across the columns, and each of said groups having a transverse extent exceeding the floor thickness, thereby forming a plurality of similarly extending inclosing floor slabs, other groups of reinforcing members extending through the floor transversely of the first groups adjacent the lower face between said first groups and adjacent the upper face across said first groups, each of said last groups having a transverse extent exceeding 95 the floor thickness so as to form a second series of inclosing floor slabs extending transversely between the first series of inclosing floor slabs thereby inclosing a multiplicity of inclosed floor slabs, reinforcement extending adjacent to the lower face of each inclosed slab and adjacent to and transversely of the upper face of two opposite inclosing slabs, and reinforcement similar to that last mentioned and extending transversely of said last mentioned reinforcement.

8. A monolithic structure comprising a concrete floor and a plurality of columns in substantially straight rows, groups of reinforcing members extending from column to column longitudinally through the floor adjacent the lower face between the columns and adjacent the upper face across the columns, and each of said groups having a transverse extent exceeding the floor thickness, thereby forming a plurality of similarly extending inclosing floor slabs, other groups of reinforcing members extending through the floor transversely of the first groups adjacent the lower face between said first groups and adjacent the upper face across said first groups, each of said last

groups having a transverse extent exceeding the floor thickness so as to form a second series of inclosing floor slabs extending transversely between the first series of inclosing floor slabs, thereby inclosing a multiplicity of inclosed floor slabs, a multiplicity of transversely arranged reinforcing members lying near the upper face of each inclosing slab between its ends and extending into adjacent regions of the inclosed

floor slab, and two series of crossing reinforcing members each extending through an inclosed slab and lying adjacent the lower face thereof and extending into the adjacent inclosing slab.
